HIGHWAY SHOULDER SHAPER

Silas L. Rose and Ralph Fay Harlan, Sidney, Nebr.

Application November 3, 1937, Serial No. 172,601

3 Claims. (Cl. 37—163)

This invention relates to highway or road machines especially adapted for shaping soft shoulders of a road either of a hard surface or unimproved surface type and has for the primary object the provision of a device of this character which may be readily adjusted to meet with varying road conditions and will be efficient, durable and economical to construct and may be pulled by a tractor, motor truck or any other draft medium.

With these and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a top plan view illustrating a road machine constructed in accordance with our invention.

Figure 2 is a side elevation illustrating the same.

Figure 3 is a rear elevation illustrating the device.

Figure 4 is a front elevation illustrating the device.

Figure 5 is a fragmentary vertical sectional view illustrating means of adjusting the pitch of the mold board and its blade and also showing means whereby the angle of the mold board and blade with respect to the line of draft may be varied.

Figure 6 is a detail vertical sectional view showing a front wheel of the caster type.

Referring in detail to the drawings, the numeral 1 indicates a main frame of elongated formation supported at its rear end by a rear wheel 2 journaled on an axle 3 carried by brackets 4 fixed on the main frame. The forward end of the main frame is supported by a front wheel 6 of the caster type so that the device will readily track the draft medium which may be a tractor, motor truck or some other medium or if desired this device may be coupled in any suitable manner for operation in conjunction with the conventional type of road grading machine principally employed for shaping the ground of an unimproved road.

A super-structure is mounted on the main frame 1 and extends laterally thereof and has journaled thereon crank shafts 7 and 8 each including a crank 9. Worm gears 10 are secured on the shafts 7 and 8 and mesh with worms 11 connected to operating shafts 12 by universal joints

13. The operating shafts 12 are capable of being rotated in either direction by hand wheels 14 and are suitably journaled on the main frame. The operating shafts 12 being rotatable in either direction will permit an operator to raise and lower the cranks 9, as desired.

The rear end of the super-structure has secured thereto an arm 17 carrying a vertically arranged journal 18 for supporting an axle 19 on the rear wheel 20. The rear wheel trails the 10 moldboard and blade thereof and which will be hereinafter more fully described. The wheel 20 and its mounting is of the caster type.

An auxiliary frame 14' converges towards its front end and has the latter-named end pivotally and adjustably connected to a support 15, as shown at 16. The support 15 is secured on the forward end of the main frame and extends laterally thereof. Links 21 connect the cranks to opposite sides of the auxiliary frame adjacent the rear end thereof.

A moldboard table 22 is pivoted at 22' on the auxiliary frame 14' adjacent the rear end of the latter and underlies said auxiliary frame and carries a removable bolt 23 adapted to extend through any one of a series of openings 24 formed in an anchor plate 25 fixed on the auxiliary frame. The openings and bolt permit the moldboard table to be adjusted about its pivot 22' in either direction. Curved arms 26 are fixed on the moldboard table and have pivoted thereto a mold board 27 carrying a removable blade 28. Arms 29 are pivoted on the moldboard and adjustably secured to the arms 26 whereby the inclination of the moldboard and the blade may be varied. The horizontal adjustment of the table permits the mold board and its blade to be adjusted relative to the line of draft. The cranks are employed for raising and lowering the mold board and the blade and being of the construction described will permit the operator to adjust the inclination of the blade relative to a horizontal plane.

A coil spring 30 is connected on the main frame and has secured thereto a flexible element 31 45 trained over a pulley 32 journaled on the super-structure and connected to the auxiliary frame. The auxiliary frame is free to move upwardly and downwardly by the actuation of the cranks due to the fact that the spring 30 will elongate 50 and contract.

A machine of the character described is simple to operate and economical to construct and may be handled by a single operator standing on the main frame at the hand wheels 14. This ma- 55

chine will permit shaping of soft shoulders to be easily accomplished through the use of a draft medium of a minimum horse power.

What is claimed is:

- 5 1. A machine for repairing shoulders of roads comprising a main frame, supporting wheels for the main frame, a super-structure carried by the main frame and projecting laterally thereof, a supporting wheel connected with the outer end 10 of the super-structure, an auxiliary frame pivoted to the forward end of the main frame and lying underneath the super-structure, grading means carried by the auxiliary frame, and individual control means connected with opposite 15 sides of the auxiliary frame for adjusting the grading means relative to the road bed.
2. A machine for repairing shoulders of roads comprising a main frame, supporting wheels for the main frame, a super-structure carried by the main frame and projecting laterally thereof, a supporting wheel connected with the outer end 20 of the super-structure, an auxiliary frame pivoted to the forward end of the main frame and lying underneath the super-structure, grading means carried by the auxiliary frame, individual control means connected with opposite 25 sides of the auxiliary frame for adjusting the grading means relative to the road bed, each of said individual control means comprising a first shaft extending longitudinally of the main frame, a second shaft projecting laterally therefrom and operatively connected with one side of the auxiliary frame, and a hand wheel connected with the first shaft near the forward end of the main frame.

means relative to the road bed, and means co-operable on the auxiliary frame and the grading means for varying the angularity of the latter with respect to the direction of travel of the machine.

3. A machine for repairing shoulders of roads comprising a main frame, supporting wheels for the main frame, a super-structure carried by the main frame and projecting laterally thereof, a supporting wheel connected with the outer end 10 of the super-structure, an auxiliary frame pivoted to the forward end of the main frame and lying underneath the super-structure, grading means carried by the auxiliary frame, individual control means connected with opposite 15 sides of the auxiliary frame for adjusting the grading means relative to the road bed, each of said individual control means comprising a first shaft extending longitudinally of the main frame, a second shaft projecting laterally therefrom and 20 operatively connected with one side of the auxiliary frame, and a hand wheel connected with the first shaft near the forward end of the main frame.

SILAS L. ROSE. 25
R. F. HARLAN.
